UNITED STATES PATENT OFFICE.

MARION R. McDANIEL, OF OAK PARK, ILLINOIS, ASSIGNOR TO HARRY V. CHURCH, OF CICERO, ILLINOIS, TRUSTEE FOR NATIONAL ASSOCIATION OF SECONDARY SCHOOL PRINCIPALS.

DESIGN FOR A BADGE.

Application filed May 21, 1923. Serial No. 6,233. Term of patent 3½ years.

To all whom it may concern:

Be it known that I, MARION R. McDANIEL, a citizen of the United States, residing at Oak Park, in the county of Cook and the State of Illinois, have invented a new, original, and ornamental Design for Badge, of which the following is a specification, reference being had to the accompanying drawing, forming a part thereof.

The drawing is a face view of a badge embodying my new design.

I claim:

The ornamental design for a badge substantially as shown.

MARION R. McDANIEL.
